FURNACE PIPE CONSTRUCTION

Filed June 15, 1925

Inventor

Geo. Harms,

By *L. M. Thurlo*

Attorney

UNITED STATES PATENT OFFICE.

GEORGE HARMS, OF PEORIA, ILLINOIS.

FURNACE-PIPE CONSTRUCTION.

Application filed June 15, 1925. Serial No. 37,390.

This invention pertains to hot air pipes or heating pipes of that type designed to be placed in walls and partitions for conveying heated air from a heating source to 5 rooms to be supplied therewith.

More particularly the invention has to do with pipe sections of rectangular form adapted to be fitted into one another for building up a "stack" within a wall or partition for heat conducting purposes, though 10 equally adapted for other uses where air is to be conveyed.

An object of my invention is to furnish a construction that will admit of placing together a series of pipe sections by a double locking arrangement, the means for locking being so disposed that there will be no danger of its being damaged through rough handling or chance blows such as would 20 prevent said sections being properly assembled.

Another object is to furnish means for double locking the sections of a pipe of the nature described and to dispose the same 25 at positions on each section distant from the ends of the latter so that said means cannot become misshapen during handling.

Still another object is to provide a dual form of locking means for pipe sections so arranged that but one of said means may be engaged with that of a companion section as a preliminary step in assembling pipe sections and for a purpose to be made known herein.

35 A further object is the construction of a pipe section, having spaced walls, wherein the portion of the outer wall which nests with the companion portion of a companion section is slanted inwardly in the direction of the inner wall and the terminal end of the section, said outer wall portion including spaced beads or shoulders paralleling the said end of the section to engage correspondingly disposed beads or shoulders of 40 said companion section, the purposes and advantages of which will appear herein.

Besides these objects the invention seeks 50 to provide a novel construction in a double pipe all of which will be made known in the following description aided by the accompanying drawing forming part hereof wherein:

55 Figure 1 illustrates in perspective a portion of a furnace-pipe section in accordance with my invention.

Figure 2 is a longitudinal section, much enlarged, of parts of two pipe sections showing their partial engagement for a preliminary locking thereof, and

Figure 3 is a similar figure showing the 60 complete engagement or the dual locking of the two sections.

Figure 4 is a slightly modified form of the invention.

In the past, pipe sections of the type 65 named herein have included an arrangement whereby they may be engaged with one another so that they will be held from movement relatively, and one of the forms known has included a form of double locking arrangement but the locking means have been 70 so placed on each section that in being at the extreme end thereof one of them is always subject to damage during handling so that having become misshapen the sections 75 cannot be assembled in proper locking position if indeed engagement can be effected at all.

One of my purposes, therefore, is to provide a construction wherein the locking 80 means is disposed inward from the extremity of the section where it is protected and where it will not be subject to distortion during rough handling so that sections of 85 pipes can, therefore, always be assembled without difficulty and will always have a snug and proper fit.

A portion of a pipe section according to 90 my invention is shown in Figure 1 and is made up of a customary inner wall 1 and an outer wall designated in general by the character 2, the form of the latter being best shown in Figures 2 and 3, the two walls being separated as usual to create an air 95 space 3. The edge of said outer wall 2, or what may be termed its end, is recurved and lapped over the end of the inner wall as at 4, there being also lapped with it a brace 5 whose form and purpose will be 100 made known presently. The said outer wall 2 is outwardly flared from the lap 4 about as shown at 6, thence having an outwardly projecting shoulder or locking bead 7 created by bending the metal at 8 slightly inward toward the wall 1, and from thence the wall 105 extends at a less abrupt angle, or more nearly parallel to said wall 1, but gradually flaring outwardly, and some distance from said locking bead 7 the said wall 2 extends still further outwardly to form a somewhat abrupt 110

shoulder or abutment 9, then continuing parallel to said inner wall 1. The slanting wall may be integral with the outer wall 2 as in Figures 1 and 2, or it may be a separate part as in Figure 4. Substantially midway between the shoulder or abutment 9 and the second locking bead 7 a bead 10 is created by creasing the metal inwardly toward the wall 1, and it may be seen that the slant 10 of the described outer wall is in the general direction of the inner wall from the abutment 9 to the extremity of the pipe section, this being true of a companion section to be referred to later as the female portion of the 15 structure. This form provides for easy nesting of the sections in one another since one may easily enter into the other with a minimum distance of lateral springing movement of the metal as the beads or shoulders pass 20 one another. Yet the said beads when interlocked form a most positive holding means for walls which, without them, would readily separate. But while the beaded wall recedes in the manner shown and described I do 25 not wish to be understood as limiting myself to the particular disposition thereof.

All four sides of the rectangular pipe section may be formed in accordance with the foregoing so that the locking beads 7, 10 and 30 the angled wall portion shown in Figures 2 and 3 extend around the said four sides. The outer wall 2 is more or less yielding in the direction of the said inner wall 1 and preferably a brace 5 previously referred to is 35 provided. This is a strip of metal having a right angled bend near one end forming a foot 5'. The main portion of the brace lies against the inner wall 1 while the said foot 5' extends therefrom in the direction of the 40 wall 2 and may lie in a slightly spaced relation thereto permitting the latter wall to move slightly inward as pressure placed thereon occurs, due to the connecting of the sections. Said brace serves to limit the inward movement of the wall 2, as may be 45 seen, making for a more firm locking engagement of the sections.

Naturally, each section is provided at each 50 end with the structure described though one end carries what may be termed the male, while the other is provided with the female arrangement, the reference characters being identical except as to the use of exponents for differentiating purposes.

55 When fully engaged as in Figure 3, the lapped ends of companion sections abut upon the shoulders 9 and the beads 7 and 10 nest in one another in firm seated relation.

The use of a so-called double lock prevents 60 the sections rocking upon one another laterally and is a very desirable arrangement for the purpose, together with the fact that a stack when interlocked can be readily handled without danger of its sections becoming 65 disengaged.

Now, while the double lock feature is not in itself new as already intimated, one of my purposes as stated earlier herein is that of spacing the beads or shoulders inwardly from the extremities of the sections where 70 neither can be subjected to shocks or blows that would otherwise tend to bend, break, or mash them out of shape, especially the outer one. It is noted, that the ends of the sections at 4 take any such abuse while the beads 7 75 and 10 lie well inward therefrom where no damage thereto can result. And by folding together the inner and outer walls together with the brace 5 a double strengthening of 80 the ends results so that there can be no great injury to the same.

Another advantage in the locking means as provided by me is that the sections can be locked in a preliminary manner, so to speak, by engaging the first meeting beads 7, 85 10 as in Figure 2, and the stack so assembled can be readily moved about more conveniently than separate sections, and that the stack may be elevated to position in a wall without danger of the sections becoming disengaged from one another, whereupon if a desired position is found correct, or if certain of the sections are to be removed they may be readily separated, and the balance of 90 them forced together in the double locked 95 engagement. Quite often when raising a stack within a wall it is found that an obstruction prevents final placing thereof and it is then necessary to remove all or part of the sections so that such obstruction may 100 be removed. It is quite necessary that pipe sections should firmly lock together when permanently in place in the wall but in the experimental entrance of the stack the locking of the sections would lead to serious 105 trouble since more often it might be impossible to disengage said sections. Now, by providing an initial locking, which at the same time admits of easy separation, no trouble would be experienced. My structure 110 admits of this and of considerable importance in connection with this adaptability is the fact that since the beads or shoulders 7, 7' extend around the sections parallel to their ends these when engaged serve to hold 115 the sections of a stack in a perfectly straight line or with their sides all in the same plane so that when elevated the ready entrance of all of them into a narrow space will be assured.

120 Due to the form of lock used it would be quite difficult if not impossible after full engagement to separate the sections by a direct end pull, requiring that a lateral movement one on the other be resorted to 125 in order to effect disengagement. This action lifts the beads at one side from engagement allowing separation and since this lateral action cannot be made use of when a stack is in the wall the partial en- 130

gagement above described is advantageous as permitting adjustments or removals of desired sections.

While I have shown a preferred embodiment of the invention answering well the requirements in practical use the structure may be varied slightly from that shown while still within the spirit of the invention and within the scope of the appended claims.

10 In Figure 4 the slightly different arrangement is provided as showing another manner of constructing the pipe section and as making for ease of manufacture of the beaded portion. That is to say, the portion 6, 8, which in the earlier figures is an integral part of either of the wall portions 1, 2, is a separate part. In this form the upper edge at 4 of the named portion engages over the wall 1 only, i. e., without including 15 the brace 5 described, while at its lower edge it is recurved as at 12 and engages over the edge of the now shortened wall 2 and pinched or gripped upon the same.

Again, between the recurved portion 12 and the bead 10 the portion is recurved upon itself as at 11 forming a foot which lies substantially at right angles to and extends toward the wall 1 and takes the place of the foot 5' of the earlier figures.

20 The device may be constructed thus and lends itself to more ready handling during manufacture, either type described being open for use.

I claim:

25 1. A pipe section of the class described including spaced inner and outer walls joined at their ends, a portion of one of the walls near one end of said section being spaced a less distance from the other wall than the balance thereof, said portion having a pair of beads extending therefrom spaced from one another and both spaced from the end of the section, said beads forming 30 separate and independent means arranged for separately or jointly locking with those of a companion section.

2. A pipe section of the class described including spaced inner and outer walls, a portion of one of the walls near one end of said section being spaced a less distance from the other wall than the balance thereof and having a pair of beads extending from its surface lying parallel to the plane of the end of the section and so disposed that the 35 beads of a similarly formed companion section may be locked therewith in two different relative positions of the sections.

3. A pipe section of the class described including spaced inner and outer walls fixed relatively to one another at their opposite ends, one of the walls at one end of the section extending at an angle away from the other wall in the general direction of the 40 opposite end of the section, such angled wall having disposed in its length a pair of

spaced locking beads paralleling the adjacent end of the section and spaced therefrom, and a companion section similarly formed, one set of the beads of the two sections adapted to initially lock together in 45 a partial engagement of said sections, and both adapted to interlock when the sections are fully nested.

4. A pipe section of the class described including spaced inner and outer walls 50 fixed relatively to one another at their opposite ends, one of the walls at each end of the section extending at an angle away from the other wall in the general direction of the opposite end of the section, such angled walls 55 having a pair of locking beads spaced from one another and lying between the ends of the section paralleling said ends, one of said beads adapted to permit initial locking with a corresponding bead of a companion section in a partial assembling of the sections, and both beads adapted to interlock with those of said companion section when the sections are completely seated in one another.

5. A pipe section rectangular in form, of the class described, having an inner and an outer wall spaced from one another connected at opposite ends, one of said walls for a part of its length extending at an 60 angle away from the other wall in the general direction of the opposite end of the section, each angled portion having a bead formed therein in two different positions spaced from one another and both 65 spaced inwardly from the marginal edges of the ends of the section and lying parallel to said ends, said angled portions being formed in the outer wall at one 70 extremity of the section and in the inner wall at the other extremity of said section, the bead nearest the extremity of the section adapted to interlock with a similarly 75 placed bead of a companion section whereby the two sections may be initially engaged, both beads of the section adapted to interlock when the sections are fully seated upon one another.

6. A pipe of the class described made up 80 of sections each comprising an inner and an outer wall spaced from one another, the end of the outer wall of one of said sections being affixed to the end of the inner wall and extending away from the latter at an angle in the general direction of the opposite end of the section, the inner wall of a companion section being alike fixed to the outer wall and extending away from the same in the general direction of the opposite end of that section, the last named section adapted to receive the first named section into it, and both sections having in each of the described angled portions thereof a pair of spaced beads spaced inward from 85 the ends of their respective sections, one of

the beads of a section adapted to interlock successively with both beads of the other section as the said sections are brought to seating positions.

7. A pipe of the class described made up of sections each comprising an inner and an outer wall spaced from one another, the end of the outer wall of one of said sections being affixed to the end of the inner wall and 10 extending away from the latter at an angle in the general direction of the opposite end of the section, the inner wall of a companion section being alike fixed to the outer wall and extending away from the same at an 15 angle in the general direction of the opposite end of the section, the last named section adapted to receive the end of the first named section into it, and both sections having in each of the described angled portions there- 20 of a pair of spaced beads spaced inward from the ends of their respective sections, the outermost beads of the sections adapted to engage one another in the initial nesting action to hold said sections relatively, 25 and then to engage the innermost beads in the final or complete nesting of such sections.

8. A pipe of the class described made up of sections each comprising an inner and an outer wall spaced from one another, one of 20 the walls at one end of each of two adjacent sections being angled away from the other in the general direction of the opposite end of the section of which it is a part, the angled portion of each having a pair of 35 spaced beads spaced from the extremities of the section, the bead nearest the end of a section adapted to interlock either bead of the other section.

9. A rectangular pipe section of the class 40 described including two walls, the ends of the walls at one end of the section having a fixed relation, one of said walls extending away from the other wall at an angle thereto and away from said end of the section and 45 having spaced relation to said other wall, the angled portion having a pair of parallel spaced beads formed therein spaced from the end of the section to engage like beads of a companion section, said beads being so

disposed that they engage one another in 50 successive order in the nesting act, and a brace fixed with respect to the said walls, lying between the same and having an extension projecting in the direction of the wall having the angled portion, said extension being normally spaced from such angled portion and adapted for limiting the movement of the same in the direction of the opposite wall. 55

10. A pipe section or unit of the class described including in its construction spaced 60 inner and outer walls each substantially paralleling one another for a part of their lengths, the outer wall terminating at one end of the section in a portion bridging the space between said walls, said portion extending in one continuous general slanting direction toward the end of the inner wall and at its end engaging the latter, there being a pair of beads formed in said portion paralleling the plane of the end of the 70 section, one or both beads adapted to interlock with like beads of a companion section, said beads being spaced both from the extremity of the section and from each other and both lying between the planes of the 75 walls, that part of said portion lying between the beads slanting in said general direction toward the inner wall.

11. A rectangular section or unit of the class described having spaced inner and 80 outer walls each terminating at one end in a portion bridging the space between said walls, said portion extending in one continuous general slanting direction toward the end of the companion wall and at its extremity engaging the end of the latter, there being a pair of beads formed in each portion paralleling the planes of the ends of the section both adapted to interlock with like beads of a companion section, said beads being spaced both from the extremity of the section and from each other, and both lying between the planes of said walls, that part of said portion lying between the beads 85 slanting in said general direction toward the 90 said companion wall.

In testimony whereof I affix my signature.
GEORGE HARMS.
